UNITED STATES PATENT OFFICE.

URQUHART WILCOX, OF BUFFALO, NEW YORK.

BOAT-HULL.

1,258,728.

Specification of Letters Patent. Patented Mar. 12, 1918.

Application filed May 20, 1916. Serial No. 98,813.

To all whom it may concern:

Be it known that I, URQUHART WILCOX, a citizen of the United States, residing at Buffalo, in the county of Erie and State of New York, have invented new and useful Improvements in Boat-Hulls, of which the following is a specification.

This invention relates to a hull which is more particularly designed for small or toy boats although some features of the same may also be advantageously employed in boats of larger sizes.

The object of this invention is to provide an improved construction of boat hulls of this character in which the more difficult work may be executed by machinery in a factory and then put on the market leaving the purchaser to do only the work of assembling and fitting together of the parts into the form of a completed boat, thereby enabling this hull to be purchased in knock-down form and not only provide a fascinating and instructive pastime while completing the boat at home but also insuring turning out a well formed and strong hull.

In the accompanying drawings:

Figure 1 is a side elevation of the boat hull embodying my invention with a portion of the skin broken away. Fig. 2 is a vertical transverse section taken on line 2—2 of Fig. 1. Fig. 3 is a vertical longitudinal section of the hull taken on line 3—3, Fig. 2. Fig. 4 is a top plan view of the boat hull with the deck or covering removed. Figs. 5 and 6 are top and bottom plan views respectively of the keel which is constructed in accordance with my improvements.

Similar characters of reference indicate corresponding parts throughout the several views.

1 represents the longitudinal keel or backbone of the boat hull which is preferably bow-shaped having its concave side facing upwardly and provided at its front with an upwardly and forwardly extending stem post 2 and with an upwardly and rearwardly extending stern post 3. In somewhat larger boats, however, these posts may be constructed separately from the keel proper and bolted thereto and strengthened by stem or stern knees as is the more usual and customary practice. The upper portion of the keel is provided with a plurality of transverse grooves or notches 4 each of which has a lower horizontal and upwardly facing flat surface 5 and two flat vertical side walls 6

which extend upwardly from opposite sides of said lower horizontal surface 5. A plurality of transverse bulkheads, ribs or sawed-to-shape frames 7 are provided each of which has a thickness equal to the width of the lower horizontal flat surface 5 which thus permits the lower part of each of said bulkheads to be moved vertically downwardly into one of said notches 4 so that when said bulkhead is in position and preferably glued in said notch, it is secured to said keel and held against displacement thereon. The different bulkheads are also properly spaced longitudinally along the keel and are all positioned parallel to each other and perpendicular to the keel, thereby expediting assembling of the parts and insuring the proper positioning of the same without regard to the particular skill of the builder. The shape of each of the bulkheads varies to correspond with the desired shape of the hull of the boat and the desired fullness of the hull lines may be obtained with mathematical exactitude because these bulkheads are machine made and the hull form will be permanently retained because they are sawed to shape so that no deformation, such as occurs with ordinary bent ribs is possible.

Adjacent to the lower ends of the bulkheads, the keel 1 is provided on its lateral sides with longitudinal rabbets or furrows 8 which extend continuously from the upper part of the stem post 2 to the upper part of the stern post 3. Starting with the garboard-strake, and then continuing with the bilge and sheer strakes forming the planking or skin 9 of the hull these strakes are laid one by one over the lateral curved edges of the bulkheads, and properly secured thereto, the planks next to the keel being fitted into the rabbets 8 so that their outer surfaces are flush and join in a smooth even curve with the outer curved surface of the keel, as best shown in Fig. 2. It will be noted that the horizontal width of the keel is somewhat greater at its middle portion this construction decreasing the total width of planking of the midship sections and thereby decreasing the objectionable taper of the individual planks inasmuch as this width of planking is caused to be made nearly uniform at all the transverse sections. This truss like keel construction also strengthens that portion of the same which is subjected to the maximum bending strain.

Over the top edges of the bulkheads and the upper flat surfaces of the stem and stem posts is laid a deck or covering 10 which may be slightly raised or arched in the middle, as best shown in Fig. 2, so as to prevent the accumulation of water on top of said deck, this being accomplished by properly sawing the upper part of each of the bulkheads so that the central part of the top

10 edge is higher than the ends.

11 is a balancing fin or stabilizing center-board which is secured at its upper edge to the flat bottom face 12 of the keel by means of screws 13 or otherwise.

15 14 represents the rudder arranged at an angle adjacent to the outer side of the stern post and pivotally supported by a pin 15 projecting from the upper end of the rudder into a bearing opening 16 in the upper rear-

20 wardly overhanging part of the stern post, and a pivot screw 17 extending upwardly through a lug 18 on the rear end of the center board and entering the lower end of the rudder, said pivot screw 18 and pin 15 being arranged axially in line.

25 The boat hull is so simple in its actual

manual construction as to insure a well proportioned handsome craft without the exercise of undue patience and at a very reasonable outlay. No special tools or apparatus are necessary in its building and the most precisely scientific and symmetrical form of hull may be obtained by a youth with scant chance for bungling. Furthermore, the hull will stand severe abuse and is 30 readily repaired if need be, and broken parts can be readily replaced so as to form water displacing compartments which are not liable to leak.

35 I claim as my invention:

40 A boat hull comprising a keel having a downwardly curved upper side provided at its forward end with a stem post, and a stern post formed at the rear end of said keel, a transverse bulkhead secured only at its 45 lower edge to said keel, a skin or planking secured to said keel and bulkhead, and a deck laid over said bulkhead and said stem and stern posts and separated by an intervening space from the keel between said 50 stem and stern posts.

URQUHART WILCOX.
